Primary Examiner — Cathron C Brooks(74) *Attorney, Agent, or Firm* — Budzyn IP Law, LLC(57) **CLAIM**

The ornamental design for a bollard luminaire, as shown and described.

DESCRIPTION

FIG. 1 is a front, upward perspective view of a bollard luminaire;

FIG. 2 is a front, downward perspective view thereof;

FIG. 3 is a front elevational view thereof, the rear elevational view being identical thereto;

FIG. 4 is a right side elevational view thereof, the left side elevational view being identical thereto;

FIG. 5 is a top plan view thereof; and,

FIG. 6 is a bottom plan view thereof.

The broken lines in the Figures are included for the purpose of illustrating unclaimed portions of the design and form no part of the claimed design.
